DESIGN FOR GOGGLES

Otto W. Heinz, Pittsburgh, Pa.

Application October 25, 1945, Serial No. 123,173

Term of patent 14 years

(Cl. D57—1)

To all whom it may concern:

Be it known that I, Otto W. Heinz, a citizen of the United States, residing at Pittsburgh, in the county of Allegheny and State of Pennsylvania, have invented a new, original, and ornamental Design for Goggles, of which the following is a specification, reference being had to the accompanying drawing, forming a part thereof.

Fig. 1 is a front elevational view of goggles

showing my new design; Fig. 2 is a top plan view thereof; Fig. 3 is a rear elevational view; and Fig. 4 is an end elevational view of the goggles.

The head strap has been shown fragmentarily in Figs. 1, 3 and 4 for convenience of illustration.

I claim:

The ornamental design for goggles, as shown and described.

OTTO W. HEINZ.
